TEMPERATURE-RESPONSIVE DEVICE

Imre J. Barsy, Lancaster, Pa., assignor to Armstrong Cork Company, Lancaster, Pa., a corporation of Pennsylvania

Application May 24, 1947, Serial No. 750,275

9 Claims. (Cl. 136—4)

1

This invention relates to a temperature-responsive device and, more particularly, to a temperature control device in the nature of a probe which may be inserted into a mass of material under treatment. The invention finds particular usefulness in the field of dielectric heating and, specifically, may be used in the control of the heating of a mass of cork composition and a binder being molded under heat and pressure, the curing of the binder being effected by dielectric heating.

An object of my invention is to provide a temperature-responsive device of a compact nature which may be readily inserted into and withdrawn from a mass of material under treatment.

A further object of my invention is to provide a multiple unit temperature-responsive device in the form of a probe which may be disposed within a body under treatment to provide multiple control circuits for the heating apparatus associated therewith.

Another object of my invention is to provide a probe containing within it a plurality of temperature-responsive elements effective for initiating multiple controls in dielectric and resistance heating equipment associated therewith.

The provision of a rugged assembly arrangement, permitting the use of both a thermocouple and a fine wire resistance element or two or more thermal elements within the same tube for effecting heat control by means of associated equipment, the control being effected independently through different circuits, is another object. Additional objects will become apparent upon further consideration of this specification, including the following detailed description of the invention in conjunction with the accompanying drawing in which:

Figure 1 is an enlarged view, partly in section and partly in elevation, showing the device of the present invention;

Figure 2 is an enlarged sectional view taken on the line II—II of Figure 1;

Figure 3 is a still further enlarged sectional view showing the fine wire resistance element and its associated support and connectors;

Figure 4 is a perspective view of an end spacer forming part of the device;

Figure 5 is an enlarged sectional view of a probe tip incorporating temperature-responsive means of a modified construction;

Figure 6 is a diagrammatic view showing a wiring arrangement employing the device of Figures 1 to 4; and

Figure 7 is a diagrammatic view showing a

wiring arrangement employing the device of Figure 5.

Referring first to Figures 1 to 4 which illustrate one embodiment of the invention, there is disclosed a probe which is made up of a socket 2 which may be screw threaded, as indicated at 3, to receive a standard electrical connector, such as an "Amphenol" connector. A tube 4 projects from the coupling 2 and is received therewithin. The tube 4 is flanged at its inner end, as indicated at 5, and is held in fixed position by a plug 6 which is screw threaded and is received within the socket 2, engaging complementary screw threads provided therein. It will be noted by reference to Figure 1 that the tube 4 lies in engagement with a substantial portion of the socket 2, and when clamped at the flange 5 by the plug 6, the tube will be held firmly in position against both axial and radial displacement.

The device is adapted to be inserted mechanically into a mass of material under treatment, and it is essential, therefore, that the tube be of relatively small diameter so as not to damage the body of material into which it is inserted, and since the insertion and removal are to be mechanically accomplished, the device must be rugged. Where the material under treatment is a cork composition held under compression in a mold, it has been found that a force between about 50 and 55 pounds is required to insert the probe. I have found that the tube 4 may be formed of "Inconel" which is an alloy of 80% nickel, 13% chromium, and the balance iron. It is sold by International Nickel Company, Inc. The material is resistant to corrosion and to heat and retains its strength after repeated heating and cooling. It has good resistance to bending and successfully resists oxidation. In a device for use in a cork composition baking process, the tube may have an outside diameter of but .140" and a length of about 10 $\frac{1}{4}$ ". The showing of all of the views is enlarged for the sake of clarity. Figure 1 is generally in the scale of about two inches equal one-inch.

Figure 4 is provided with a tip 7 which closes the end of the tube 4. The tip is provided with a rounded or ogival nose so as to facilitate the insertion and removal of the probe into and from the mass under treatment. The tip 7 is made of a wear-resistant and heat-conducting material, such as an alloy of copper and beryllium. The tip should be formed of a good wear-resistant material and must be of a material which will rapidly conduct heat, for a heat-sensitive element or elements are positioned within the

tip, as will be more fully hereinafter described, and it is essential to rapidly conduct heat from the mass under treatment to the heat-sensitive element or elements in order to effect proper control of the heating.

In the embodiment shown in Figures 1 to 4, the heat-sensitive elements consist of a thermocouple 8 and a fine wire resistance element 9, both being positioned within the probe, as shown in Figure 2. Both elements are responsive to temperature within the mass under treatment upon insertion of the probe therein, and each may serve to control a separate electric circuit. For example, the element 8 may control the supply of high frequency power to the mass under treatment, cutting off the supply of power when the mass attains a desired temperature. The resistance element 9 may be connected in a circuit with another heat-responsive resistance element to control the supply of high frequency power to the mass in accordance with differences in temperature between that attained within the mass and that of the mold element, as discussed in the copending application of George E. Gard, Serial No. 702,559, filed October 10, 1946, now 25 Patent No. 2,508,382, assigned to my assignee. A wiring arrangement of this type has been diagrammatically illustrated in Figure 6 where numbers corresponding to those of Figures 1 to 4 have been applied, and the other elements have been provided with identifying indicia. The device of this invention is not limited, however, to any particular control circuit. In fact, it may be used for initiating indicating means rather than effecting controls or may be used for a combination of both purposes.

The tip 7 is provided with a chamber 10 which receives an anchoring lead 11 which is silver soldered to the tip 7. The anchoring lead may, and preferably does, constitute one element of a two-element thermocouple. The anchoring lead 11 may be a constantan thermocouple wire of B & S gauge No. 28. The portion received within the tip 7 will be bare so that a proper contact with the tip and with the other element of the thermocouple may be made, but the remaining portion of the constantan element will be insulated; a glass fiber insulation with a silicone impregnant has been found acceptable. As shown in Figure 2, the element 11 extends throughout the length of the probe, and preferred practice is to have the wires extend to the connector which is received within the screw-threaded opening 3 in the socket 2. The wires are shown out of scale in Figures 2 and 5 to illustrate their positioning. Normally, they substantially completely fill the chambers in which they are received.

The other element of the thermocouple is formed of B & S gauge No. 28 copper thermocouple wire which is indicated by the numeral 12 in Figure 2 and is attached to the constantan element 11. The tip 7 is recessed to provide a chamber 13 which receives the thermocouple elements, and after insertion, the chamber 13 is 65 filled with silver solder. The copper element, like the constantan element, is bare at the portion received within the tip but is insulated from that point to the point of connection at the base of the socket 2. Glass fiber insulation impregnated with silicone is satisfactory.

The fine wire resistance element 9 is illustrated in Figures 2 and 3. The wire is indicated by the numeral 14. I have found that an alloy of 51% nickel and 49% iron, known as "Driver" 75

Harris No. 52" alloy, enamel covered, is acceptable. In the embodiment illustrated, the wire is 0.001" in diameter and has a resistance of 280 ohms per foot and 0.0029 ohm/ohm/°C. 5 temperature coefficient of resistance in the range of 20-500° C. and a coefficient of linear expansion of $95 \times 10^{-7}/^{\circ}\text{C}$. at 20-500° C. In the embodiment illustrated, the fine wire resistance element is 0.5 of an inch long and has a resistance of 13.5 ohms. A supporting tube 15 is provided for the fine wire resistance element. The tube 15 is slotted at 16 to provide an opening for the reception of the wire 14. The tube may be formed of any good dielectric which is resistant to heat, and I have found that a material known as "Mycalex 400," which is sold by the Mycalex Corporation of America, consisting of a glass-bonded mica insulation, is satisfactory. The coefficient of expansion of this material ($100 \times 10^{-7}/^{\circ}\text{C}$. in the range of 25-200° C.) is substantially equivalent to the coefficient of expansion of the fine wire 14 so that upon heating and cooling of the probe in operation, the wire and the support will expand and contract in about equivalent amounts, thus avoiding any stressing of the wire beyond its elastic limit. The volume resistivity of the dielectric is 2×10^{15} ohms-cm.

The wire 14 is electrically connected to an outer supporting connector 17. The connector 17 is received within the tube 4 and is secured to the tip 7, the tip being turned down and shouldered so as to frictionally receive the connector 17. There is provided an opening 18 which extends from the inner edge of the connector 17 and opens into a recessed portion 19 which is turned on the connector 17. The wire 14 passes through the opening 18 and is soldered to the connector 17, as indicated at 20, the solder being carefully filed down so as to lie below the upper surface 21 of the connector to permit ready insertion of the connector into the tube.

The opposite end of the wire 14 is received within an inner connector 22 which corresponds generally to the outer connector 17. The connector 22 is received within the tube 4 and is frictionally secured to the tube 15. The connector 22 is spaced from the tube 4 and is insulated therefrom, preferably by means of a silicone enamel coating which is applied to the outer surface of the connector. The inner surface of the tube 4 may also be coated with a silicone insulating enamel, as indicated at E in Figure 2, to insure proper electrical insulation of the connector 22 from the remaining parts. An opening 23 is provided in the connector 22, and the fine wire resistance element 14 passes through the opening 23 and is soldered to the connector 22, as indicated at 24 in Figure 3.

An insulating ring 25, which is shown in Figures 2 and 4, is received within the tube 4, being bottomed against a shoulder 26 constituting the base of a bore extending from the tip end of the tube 4. The insulating ring 25 is formed of nylon, and a nylon material known as Du Pont FM-1 will be acceptable for the purpose. The insulating ring 25 must be made of some material which will withstand the temperatures encountered in use of the probe and is, preferably, made of a material which may be readily machined and which possesses sufficient toughness for the purpose intended. The ring 25 serves a number of functions, including the backing up of the elements which are received within the tube, thus preventing potential axial displacement thereof.

along the length of the tube in a direction away from the tip 7 so that when the elements are assembled within the tube 4, there will be no end play in an axial direction; all of the components being fitted closely together without spacing therebetween. It also serves as an element which may be readily machined and inserted into the tube 4 to compensate for any minor differences in length between the operating portion of the tube 4 and the total length of the various component elements which are inserted therein. It must be remembered that the probe is of relatively small cross section, and the elements are minute in size so that a small part of an inch difference in length is important and must be compensated for at the time of assembly. The insulating ring has a central opening 27 through which the thermocouple wires 11 and 12 pass and is provided with a slot 28 through which a copper lead 29 for the fine wire resistance element 9 passes. The lead 29 is soldered within an opening 30 drilled in the inner end of the connector 22, as illustrated in Figure 3. Since the connector 17 is frictionally fitted to the tip 7 and the elements 11 and 12 of the thermocouple 8 are soldered to the tip 7, either one of the elements 11 and 12 may constitute a lead for the end of the fine wire resistance element 14 connected to the connector 17. The lead 29, together with the thermocouple wires 11 and 12, extend through the tube 4 and through a central opening 31 in the plug 6 (Figure 1) and are connected to the prongs of the male element of the "Amphenol" connector previously referred to.

It will be observed by reference particularly to Figure 2 that the tip 7 is shouldered, as indicated at 32, to receive the end of the tube 4, and the curved surface 33 of the tip 7 extends from the shouldered portion 32 to the point of the tip. Thus, the end of the tube 4 is protected against damage, and insertion of the probe is facilitated by the curved surface of the tip 7 which merges smoothly into the cylindrical surface of the tube 4. The tip 7 is preferably soldered to the tube 4 because of the size of the parts. It may be attached by means of screw threads or other fastening means, however, or it may be frictionally fit, as shown in the drawings.

Figure 5 illustrates a modification of my invention in which a thermal junction constituting three thermal elements having a common positive and three negative leads are provided in a tip 34 in place of a single thermocouple and a fine wire resistance element, as shown in the other views. In this embodiment, the tip 34 is provided with a chamber 35 which receives an anchoring lead 36 which is silver soldered thereto. The lead 36 preferably forms one element of the thermocouple and may be B & S gauge No. 28 copper thermocouple wire, constituting the positive lead. The three other wires 36a, 36b, and 36c constituting the negative leads may be B & S gauge No. 28 constantan thermocouple wire. These wires are the same as the wires for the thermocouple 8 previously referred to, and they are constructed in a manner well known to the art. The thermal junction is received within a chamber 37 provided in the tip 34, and upon insertion of the wires, the chamber 37 is filled with silver solder. As in the embodiment previously described, the wires within the tip are bare but are insulated from that point back to the connection in the socket 2, preferably, using glass fiber insulation impregnated with silicone. In this embodiment, the tube has been designated with the numeral 38, and the tip 34 is shouldered against the base 75

of a bore 39 provided in the tube 38. The tip is streamlined and shouldered, as in the other embodiment, to provide for easy insertion without damage to the tube.

Where two or more thermal elements are incorporated in the probe, they may be used for actuating independent circuits. For example, where the arrangement shown in Figure 5 is employed, one thermal element may serve to actuate a device for indicating the temperature within the mass. A second may be used to initiate a control effective for discontinuing the supply of high frequency power to the mass upon its attainment of a desired temperature, and the third may be interconnected with another thermocouple positioned in a mold element to control the supply of high frequency power to a mass under treatment in accordance with differences in temperature between that attained within the mass and the temperature of the mold element. Such an arrangement is diagrammatically shown in Figure 7. Numbers corresponding to those of Figure 5 have been applied to corresponding parts and other elements have been provided with identifying indicia.

While a single thermocouple is shown in Figures 1 to 4 and three thermal elements with a common positive and three negative leads are shown in Figure 5, the number incorporated in the structure of my invention may be varied, depending upon the requirements of the particular indicating or controlling functions to be effected. The size of the tube 4 and the socket 2 will have a limiting effect upon the number of wires which may be used, but the dimensions of the probe may be increased for some types of materials, and this will permit the use of more wires, if necessary.

While I have illustrated and described a preferred embodiment of my invention, it will be understood that the same may be otherwise embodied and practiced within the scope of the following claims.

I claim:

1. A temperature-responsive device comprising a probing tube, the forward end of which is adapted to be inserted into a mass, said forward end constituting a heat-sensitive zone, a fine wire resistance device insertable within the forward end of said tube as a unit comprising an insulating tube having a recess extending longitudinally on the outer surface thereof, a heat-responsive fine wire resistance thermometer element received within said recess, a connector secured to one end of the insulating tube and connected to one end of said fine wire resistance element, a second connector secured to the other end of the insulating tube and connected to the other end of said fine wire resistance element, a lead connected to said first-mentioned connector, means for insulating said first-mentioned connector from said probing tube, and means closing the forward end of said probing tube.

2. A multiple unit temperature-responsive device comprising a probing tube, the forward end of which is adapted to be inserted into a mass said forward end constituting a heat-sensitive zone, a tip attached to the forward end of the probing tube, said tip being provided with an opening to receive a thermocouple, a thermocouple in said opening, an insulating spacer received within said probing tube, an electrical connector disposed within said probing tube in abutting relationship to the spacer, a hollow insulating tube disposed within said probing tube

and receiving said electrical connector, and a second connector disposed within said probing tube and received on the opposite end of said insulating tube, said insulating tube being provided with a recess for the reception of a heat-responsive fine wire resistance thermometer element and said connectors being provided with openings for the reception and electrical connection of a fine wire resistance element, and a heat-responsive fine wire resistance thermometer element disposed within said recess and electrically connected to said connectors, said fine wire resistance thermometer element being disposed in the forward end of said tube in the heat-sensitive zone thereof.

3. A multiple unit temperature-responsive device comprising a hollow protecting tube, the forward end of which is adapted to be inserted into a mass, said forward end constituting a heat-sensitive zone, a thermocouple electrically connected to said tube, and a heat-responsive fine wire resistance thermometer element received within said protecting tube, means for connecting an end of the fine wire resistance element to the thermocouple, and means for insulating the other end of the fine wire resistance element from the thermocouple and the tube.

4. A temperature-responsive device for independently controlling a plurality of electrical circuits comprising a heat-conducting tube, the forward end of which is adapted to be inserted into a mass, said forward end constituting a heat-sensitive zone, a heat-conducting tip attached to the forward end of said tube, a thermocouple disposed within the tip, a hollow insulating tube disposed within the heat-sensitive zone of said tube, electrical connectors fitted to said insulating tube, one of said connectors being connected to said tip and the other being insulated from both the tip and the heat-conductive tube, a heat-responsive fine wire resistance thermometer element disposed within a recess in said insulating tube and electrically connected to said connectors, leads for the thermocouple passing through the opening in said insulating tube, and a lead attached to said insulated connector.

5. A temperature-responsive device comprising a stiff small diameter probing tube, a connector to which said tube is attached, a bore within said tube, a spacer of electrical insulating material disposed within said bore adjacent the inner end thereof, said spacer having a central opening therein communicating with the opening in the tube and having a recess in the periphery thereof, a fine wire resistance device received within said bore comprising a tube of electrical insulating material, said tube having a recess extending along the outer surface thereof, a heat-responsive fine wire resistance element received within said last-mentioned recess, an electrical connector fitted to one end of said insulating tube and electrically connected to one end of said fine wire resistance element, the end of said connector abutting said insulating spacer and having a lead opening therein communicating with the peripheral recess in the insulating spacer, a lead in said opening in the connector, said lead passing through the central opening in the probing tube, a second electrical connector fitted to the opposite end of said insulating tube and electrically connected to the other end of said fine wire resistance element, said connector having an opening therein communicating with the opening in the insulating tube, a heat-conducting tip having a recess and

5 received within said opening in the second connector member and having a second portion received within the bore of said probing tube, a shoulder on said tip overlying and protecting the end of said probing tube, an ogival surface on the end of said tip beyond said probing tube to facilitate entrance of the probe into a mass of material, said tip being provided with a lead chamber and with an intercommunicating thermocouple chamber, said chambers communicating with the opening in said insulating tube, an anchoring lead in said lead chamber, a thermocouple in said thermocouple chamber fixed with respect to said anchoring lead, and leads from said thermocouple extending through aligned openings in said insulating tube, insulating spacer, and probing tube.

6. A temperature-responsive device comprising a probing tube, the forward end of which is adapted to be inserted into a mass, said forward end constituting a heat-sensitive zone, a heat-responsive fine wire resistance thermometer device insertable within the forward end of said tube as a unit and comprising an insulating tube, a heat-responsive fine wire resistance thermometer element, a connector secured to one end of the insulating tube and connected to one end of said element, a second connector secured to the other end of the insulating tube and connected to the other end of said element, said insulating tube and element having substantially equivalent coefficients of expansion in the range of 25° C. to 200° C.

7. A temperature-responsive device comprising a supporting tube, a heat-conductive metal tip fitted into the tube and projecting beyond the end thereof, said tip having two chambers provided therein, a forward one of which projects toward the extremity of the tip beyond the supporting tube, and a rearward one of which is in open communication with the forward chamber, one element of a thermal junction disposed within said forward chamber and extending into said rearward chamber, a second element of the thermal junction joined to said first-mentioned element within said second chamber, and heat-conductive metal filling the chambers and joining the element in the forward chamber and thermal junction in the rearward chamber in heat-conducting relationship to said tip, whereby the temperature sensitivity of the device is enhanced.

8. A holder for a heat-responsive element comprising a socket, a tube secured to the socket, and a heat-conductive metal tip fitted into the tube and projecting beyond the end thereof, said tip having two chambers provided therein, a forward one of which projects toward the extremity of the tip beyond the supporting tube, and a rearward one of which is in open communication with the forward chamber, said forward chamber receiving one element of a thermal junction and the rearward chamber receiving a thermal junction comprising the first-mentioned element and a second thermal element joined thereto.

9. A temperature-responsive device for controlling a plurality of electrical circuits comprising a heat-conductive metal probing tube, the forward end of which is adapted to be inserted into a mass, said forward end constituting a heat-sensitive zone, a tip attached to the tube, a thermocouple attached to the tip and electrically connected thereto, a heat-responsive fine wire resistance thermometer element disposed within the heat-sensitive zone of said tube, means

electrically connecting one end of the fine wire resistance thermometer element to said tip, means insulating the opposite end of said element from the tip and tube, and insulated leads from said thermocouple and the insulated end of said fine wire resistance thermometer element passing through said tube.
